US0D1059828S

(12) **United States Design Patent** (10) **Patent No.:** **US D1,059,828 S**
(45) **Date of Patent:** **** Feb. 4, 2025**

(54) **EAR CLEANER STORAGE DEVICE**

(71) Applicant: **HEIFENG ZHIZAO (SHENZHEN) TECHNOLOGY CO., LTD**, Shenzhen (CN)

(72) Inventors: **Hong Xin**, Shenzhen (CN); **Shihong Wang**, Shenzhen (CN); **Kunsheng Chen**, Shenzhen (CN)

(73) Assignee: **HEIFENG ZHIZAO (SHENZHEN) TECHNOLOGY CO., LTD**, Shenzhen (CN)

(**) Term: **15 Years**

(21) Appl. No.: **29/954,860**

(22) Filed: **Jul. 30, 2024**

(30) **Foreign Application Priority Data**

Jan. 31, 2024 (CN) 202430067750.5

(57) **CLAIM**

The ornamental design for an ear cleaner storage device as shown and described.

DESCRIPTION

FIG. 1 is a perspective view of an ear cleaner storage device showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the ear cleaner storage device; and,

FIG. 10 is a perspective view of the ear cleaner storage device where the ear cleaner storage device in an open state. The broken lines in FIG. 9-10 showing components of the ear cleaner depict environment and form no part of the claimed design. The other broken lines in the drawings depict portions of the ear cleaner storage device and form no part of the claimed design.

1 Claim, 10 Drawing Sheets
